IMPROVEMENT IN MACHINES FOR DE-
GREASING PIPES AND THE LIKE BY IM-
MERSION IN LIQUID SOLVENTSThomas J. Kearney, Detroit, Mich., assignor to
Detrex Corporation, Detroit, Mich., a corpora-
tion of Michigan

Application August 23, 1948, Serial No. 45,658

4 Claims. (Cl. 134—105)

1

This invention relates generally to degreasing machines which are capable of accommodating tubes, rods, extrusions and the like. In the manufacture of these materials, a stage is reached in which grease must be removed from the product. This is particularly the case where the product has previously been passed through an oil quenching bath. The difficulty of removing oil and grease is greatly increased when the product, such as a tube, is both heavy and hot as is frequently the case. Therefore, the objects of this invention are, first, to provide a degreasing machine for accommodating heavy and hot tubes, rods, extrusions and the like in an automatic manner as they come out of an oil quenching bath; second, to provide a degreasing machine for the accommodation of such materials in varying lengths; third, to provide an adjustable conveyor means in a degreasing machine in which the adjustment may be made by an operator without subjecting himself to the vapors in the machine; and fourth, to provide an automatic device in a degreasing machine for discharging the materials being degreased at the conclusion of the operation. The objects of this invention may be realized by the means described in detail in the following specification.

The invention will appear more clearly from the following detailed description when taken in connection with the accompanying drawings, showing by way of example, a preferred form.

Fig. 1 is a front end view of the loading side of a degreasing machine conveniently embodying my invention.

Fig. 2 is a side elevation of the machine with parts broken away to better disclose important details and as seen looking from the left hand end of Fig. 1.

Fig. 3 is a vertical longitudinal sectional view taken as indicated by the lines and arrows III—III in Fig. 1.

Fig. 4 is a fragmentary front elevation of a discharge device and taken as indicated by the lines and arrows IV—IV in Fig. 3.

Fig. 5 is a vertical longitudinal sectional view showing an adjusting means hereinafter particularly referred to, and taken as indicated by the lines and arrows V—V in Fig. 1.

Fig. 6 is a fragmentary plan view of the adjusting means looking in the directions of the lines and arrows VI—VI in Fig. 5.

Fig. 7 is a vertical transverse sectional view of a screw adjusting means, taken as indicated by the lines and arrows VII—VII in Fig. 5; and

Fig. 8 is a vertical elevational view as seen

2

looking in the direction of the lines and arrows VIII—VIII in Fig. 1.

The preferred form selected for description herein as illustrative of the invention is a machine for degreasing heavy metal tubes as they come out of an oil quenching bath in a heated condition. It will be appreciated by those skilled in the art that the invention is equally applicable to the other materials mentioned above and to still other materials analogous thereto, and therefore it will not be necessary to specifically describe the invention with reference to such other materials.

In describing the embodiments of this invention shown in the drawings, a specific terminology will be adopted for the purpose of clarity, but it is to be understood that it is not intended thereby to limit the invention to this detailed description of illustrative embodiments thereof. Each term adopted is intended to include all equivalents thereof which operate in a substantially similar manner to accomplish a substantially similar result.

The invention may be analyzed for descriptive purposes into the following principal elements: a conventional housing comprehensively designated 9, a main upper drive shaft 10, a secondary lower shaft 11, sprockets 12 mounted fixedly on said shaft 10, and 11, conveyor chains 13, 14, and 15 in operative engagement with said sprockets 12, carriers 16 mounted on said conveyor chains 13, a solvent container 17, and a drive mechanism comprehensively designated as 22. The housing 9 includes a frame with the usual casing and a water jacket well-known in existing degreasing machines. A removable cover portion or casing 23 is provided over the main drive shaft 10. The main drive shaft 10 is mounted in the top portion of the housing 9 in conventional bearings 24 mounted on the frame of the housing 9 with capacity for vertical adjustment as shown in Fig. 5. There are two of these bearings 24, one at each end of the shaft 10, but only one is shown. This adjustment means is made up of two pairs of horizontal members 27 and 28 of channel-like cross section and attached at the ends thereof to vertical members 29 which are mounted on frame members 31 with capacity for guided vertical movement. The bearing 24 is mounted on the upper horizontal member 27 and a pair of spaced channel beams 32 are mounted between the members 27 and 28 immediately beneath the bearing 24 as strengthening supports therefore. Vertical adjustment screws 34 extend up through holes formed

in the horizontal members 27 and are supported and mounted at their lower ends on frame member 35. The upper portions of the screws 34 are threaded to receive nuts 36 and lock nuts 37, the nuts 36 providing adjustable supports for the upper horizontal member 27. The adjustment operation will be obvious from the above description in connection with Fig. 5. Air discharged upwardly through ducts 40 by a blower fan 41 removes any solvent vapor which may rise above the condensing area of the machine determined by water jacket 42 of a type well known in the art, and serves to cool the hot pipes as they leave the machine.

The conveyor chains 13, 14 and 15 are in operative engagement with the sprockets 12 and have mounted thereon the vertically spaced carriers 16. The spacing and number of chains and associated sprockets depend upon the range of lengths of tubes to be handled. By spacing the chains at small distances, short tubes can be accommodated as well as long ones. Each carrier 16 consists of a pair of converging rod-like elements which provide a slight incline of the carriers 16 for receiving and discharging the tubes 45 which are accommodated by the degreasing machine.

A solvent container 17 is mounted in the bottom of the degreasing machine and is so positioned that the carriers 16 will be dragged through the solvent as they are carried under the lower sprockets 12 rotatably mounted on shafts 11. Associated with each conveyor chain 13, 14 and 15 are U-shaped guides 50 which extend down around the lower sprockets 12 as shown in Fig. 2. Inclined receiving and discharge guides 51 and 52 are provided at the upper ends of each of the U-shaped guides 50 at the front and rear of openings 23a and 23b of the casing 23 as shown in Figs. 1, 2 and 3. These openings also permit access to adjustment means 36 and 37 without removal of any part of the machine. An inclined ejector arm 53 mounted on a rod 54 pivotally mounted on the machine frame 31 at 55 is provided for gently urging tube 45 to roll off the carrier 16 on to the discharge guides 52 as shown in Fig. 3. At times a tube 45 may become stuck on the guides 16 because of flat spots, irregularities, or distortions of the surface of the tubes or other work being treated requiring a greater pressure to dislodge the tube 45. In this event the tube 45 will continue its upward movement on the carriers 16 raising the ejector arm 53 until the offset 54a of the rod 54 contacts the shaft 10, whereupon said arm 53 will initiate movement to the tube 45 causing it to roll down the incline 52 at the discharge end of the machine. Since the ejector arm 53 may swing freely about the pivot 55 as a tube comes into contact therewith, the pressure developed from the motion of the tube is small but quite sufficient. The ejector arm 53 is guided in its movement between by a pair of angle standards 56 mounted on one of the bars 32. Normally the ejector arm 53 is supported in horizontal position as shown in broken lines in Fig. 3 by a stop bolt which is selectively engageable for adjustment into vertically arranged holes in the standards 56 to take care of the adjustments required as the main drive shaft 10 is moved vertically. In order to guide the inclined tubes 45 at each end thereof, guide plates 57, shaped as shown in Fig. 8, are provided in each end of the degreasing machine. The carriers 16 on the conveyor chains 13, 14 and 15 are lined up as between conveyor chains so

that the tubes 45 are held at a slight angle with the horizontal. This inclination of the tube induces a high rate of flow of solvent through the tube which aids in the cleaning and also insures 5 drainage of solvent from the tube before it leaves the machine. The inclination also eliminates any possibility of air binding within the tube (particularly in small diameter tubes) which would otherwise occur if the tube was immersed in the solvent in a perfectly horizontal position particularly if the tube was slightly deformed so as to produce an air pocket. It has been found that a pitch of 3" in 20' works well but the exact inclination is not critical.

The drive mechanism 22 is of a conventional form with capacity for accommodation to adjustments of the main drive shaft 10 by means of the pivotally mounted pinion 60. The motor 61 is connected by chain 62 to gear reduction box 20 63 which in turn is connected by chain 64 to the drive sprocket 65 mounted on the end of the drive shaft 10.

The solvent supply is maintained by storage tank 67, from which distribution to the solvent tanks is effected by pump 70. An inclined sheet 71 is provided over the solvent tank to act as a baffle for directing vapor from the tank into the cleaning area of the machine. Both of the tanks are provided with conventional heating means 30 (not shown) for heating the solvent.

It is to be noted that the duct 40 has branches which extend transversely beneath the receiving and discharge guides 51 and 52 respectively at the loading and unloading sides of the machine, 35 and that said ducts have inlet apertures on their tops by way of which the air is released to pass upward through the intervals between said guides.

While this invention has been described above 40 in considerable detail and certain modifications thereof suggested, it will be apparent to those skilled in the art that various other changes and modifications may be made without departing from the spirit or scope of the invention as 45 defined in the following claims.

I claim:

1. In a machine for degreasing pipes or the like, a pair of vertically spaced horizontal shafts; plural sprocket wheels at spaced intervals along 50 the respective shafts; endless conveyor chains trained about corresponding pairs of the sprocket wheels; laterally projecting pipe supporting ledges at spaced intervals on the chains; a receptacle containing liquid solvent through which 55 the pipes are passed as the chains round the lower sprocket wheels; a gravity feed guideway adjacent the upper sprocket wheels at one side for directing the pipes successively onto the ledges on the descending runs of the chains; an 60 inclined gravity discharge guideway adjacent the upper sprocket wheels at the opposite side; and pivoted ejector arms normally stopped in horizontal position somewhat below the upper sprocket shaft and having inclined portions at their 65 distal ends and adapted to be engaged from beneath by the pipes for displacing the pipes from the ledges on the ascending runs of the chains onto the gravity discharge guideway, said arms being limited in their rising movement by contact with the upper sprocket shaft so that the 70 pipes, in the event that they should stick, are forcibly dislodged for ejection from the chains.

2. In a machine for degreasing pipes and the like, a pair of vertically spaced horizontal shafts with plural sprocket wheels at spaced intervals

thereon; endless chains trained about corresponding pairs of the sprocket wheels; laterally projecting pipe supporting ledges at spaced intervals on the chains; a receptacle containing liquid solvent through which the pipes are passed as the chains round the lower sprocket wheels; a gravity feed guideway adjacent one side of the upper sprocket wheels and a gravity discharge guideway adjacent the opposite side of the upper sprocket wheels, said guideways being of open construction; means operative to displace the pipes successively from the ledges on the ascending runs of the chains onto the gravity discharge guideway; and blower means forcing air upwardly through said guideways.

3. In a machine for treating pipes and the like with hot liquid solvent, a pair of vertically spaced horizontal shafts with plural sprocket wheels at spaced intervals thereon; endless conveyer chains trained about corresponding pairs of the sprocket wheels; laterally-projecting pipe-supporting ledges at spaced intervals on the chains; a container for liquid solvent through which the pipes are passed as the chains round the lower sprocket wheels; a gravity feed guideway adjacent one side of the upper sprocket wheels and a gravity discharge guideway adjacent the opposite side of the upper sprocket wheels, said guideways being of open construction; means operative to displace the pipes successively from the ledges on the ascending runs of the chains onto the gravity discharge guideway; an open top casing in which solvent container and the conveyers are housed; cooling means surrounding the casing at a level above the solvent container; air ducts transversely beneath the respective guideways; and blower means forcing air into the ducts for release upwardly through the guideways onto the pipes.

4. In a machine for degreasing pipes and the like, a housing having in the bottom thereof a container for hot liquid solvent; a cooling jacket surrounding the housing at a level above the container for maintaining a limit level for sol-

vent vapor; horizontal shafts respectively in the upper and lower portions of the casing; endless conveyer chains trained about spaced sprocket wheels on the respective shafts; laterally projecting pipe supporting ledges at spaced intervals on the chains for passing the pipes through the solvent as the chains round the lower sprocket wheels; a gravity feed guideway extending inwardly through an opening in one side 10 wall of the casing adjacent the upper sprockets for directing the pipes onto the ledges on the descending runs of the chains; a gravity discharge guideway extending outward through an opening in the opposite side wall of the casing 15 adjacent the upper sprockets; ejector means for displacing the cleaned pipes successively from the ledges on the ascending runs of the chains onto the discharge guideway; and vertically-adjustable bearings for the upper sprocket shaft within the housing accessible for adjustment from the exterior through the aforesaid wall openings.

THOMAS J. KEARNEY.
